UNITED STATES PATENT OFFICE.

ERVIN R. HORTON, OF MEDFORD, MASSACHUSETTS.

CUFF-HOLDER.

SPECIFICATION forming part of Letters Patent No. 378,094, dated February 21, 1888.

Application filed June 18, 1887. Serial No. 241,732. (No model.)

To all whom it may concern:

Be it known that I, ERVIN R. HORTON, of Medford, county of Middlesex, and State of Massachusetts, have invented an Improvement 5 in Cuff-Holders, of which the following description, in connection with the accompanying drawings, is a specification, like letters on the drawings representing like parts.

This invention has for its object to provide 10 a cuff-holder especially adapted for ladies' use.

In accordance with this invention a strip of wire is bent at or near the middle, like a hair-pin, forming two legs, which at a point about the middle of the bent strip cross each other 15 and terminate in hooks or bent portions, which co-operate to form a separable button-receiving loop.

The legs of the holder at a point midway between the point where the legs cross each 20 other and that end opposite the button-receiving loop are bent inward toward each other, to meet, or substantially so, for a short distance, and such inwardly-bent portion is surrounded by a band. A loop will thus be presented at 25 each side of the band, that one next the hooks being adapted to be compressed to separate the button-receiving loop and that one at the end permitting a small portion of material to be drawn through it, so that a pin can be 30 quilted into the material of the sleeve, thence through the material protruding from the said loop, and entering the opening which is formed in the band, to thereby conceal the point of the pin. The loop at the end opposite the 35 separable button-receiving loop, together with the pin, forms the attaching device for the cuff-holder; and in lieu of this form of attaching device, the said loop may be omitted and the two legs made of independent pieces of 40 metal bent to present the separable button-receiving loop and the compressible loop, and joined one to the other at the end opposite the button-receiving loop, the wire forming one of the said legs being extended and overturned to 45 form a pin, the end of which may be caught beneath a suitable hook or eye, like an ordinary safety-pin.

Figure 1 shows in elevation a cuff-holder embodying this invention; Fig. 2, a side view 50 of the cuff-holder shown in Fig. 1, it being attached to a piece of material. Fig. 3 shows in

elevation a cuff-holder having a modified form of button-receiving loop. Fig. 4 shows the cuff-holder as attaching a cuff to a sleeve, and Fig. 5 shows in side view a cuff-holder having 55 a modified form of attaching device.

A single strip of wire or other suitable material is bent at or near the middle, like an ordinary hair-pin, to form two legs, 2 3, which are placed a short distance apart. The legs 60 2 3 at or near the middle of the holder thus formed are made to cross each other, and the ends of the legs are bent, as at 5, to form hooks or portions of a loop, which may be separated, when desired, by compressing the main body 65 portion of the holder. The separable loop thus formed encircles the shank of the sleeve-button.

The legs 2 3 of the holder at a point between where the said legs cross each other and the 70 end opposite the separable button-receiving loop are bent inward toward each other, to meet, or substantially so, for a short distance, and a band, 6, having a central opening, surrounds the legs at this point. A loop, 4, will 75 thus be presented at one side of the band 6, through which a small portion of the sleeve or garment may be pulled, as shown in Fig. 2, so that it may protrude sufficiently to permit a pin, 7, quilted into the sleeve outside the said 80 loop, to pass through the material protruding from within the loop, the point of said pin finally entering the central opening of the band 6. A loop, 8, will be presented at the opposite side of the band 6, the wire forming the 85 sides of which when compressed causes the button-receiving loop to separate.

It is obvious that the particular bend given to the ends of the legs may be varied somewhat, two different forms being herein shown 90 in Figs. 1 and 3, that shown in Fig. 3 being preferable, as it contains an outwardly-projecting lip to facilitate the passage of the shank of the button. It is also obvious that the particular attaching device by which the cuff-holder herein shown is attached to a sleeve—viz., the loop 4, band 6, and pin—may be used 95 for garment-supporters and the like.

In Fig. 5 I have shown a cuff-holder having a modified form of attaching device. The two 100 legs 2 3 are herein made of two independent pieces of wire bent to present the separable

button-receiving loop and the compressible loop, the legs being joined one to the other at the point indicated by the loop 4. One of the legs is extended and overturned to form a pin, 5 25, the end of which is caught beneath an open hook or eye, 26, like unto an ordinary safety-pin.

I claim—

1. As an improved article of manufacture, 10 the herein-described cuff-holder made of wire, it having a pin-attaching device, substantially as described, at one end, and a separable spring-actuated button-receiving loop at the opposite end, substantially as and for the purposes 15 specified.

2. As an improved article of manufacture, 20 the herein-described cuff-holder made of wire, it having a pin-attaching device at one end, a separable spring-actuated button-receiving 25 loop at the opposite end, and a compressible loop or middle portion, 8, formed by the legs which form the sides of the button-receiving loop crossing each other near the said button-receiving loop, substantially as and for the purposes specified.

3. The attaching device for purposes described, which consists of a loop, 4, a band, 6, having a central opening, and a pin, 7, as and for the purposes set forth.

4. In the cuff-holder herein described, a two-part or separable button-receiving loop, the extremity of one part being bent outward to form a loop, substantially as and for the purposes specified.

5. In the cuff-holder herein described, an 35 attaching device at one end to engage the sleeve, combined with two legs, 23, the ends 5 of which are bent to form a two-part or separable button-receiving loop, substantially as and for the purpose specified.

In testimony whereof I have signed my name to this specification in the presence of two subscribing witnesses.

40 ERVIN R. HORTON.
